UNITED STATES PATENT OFFICE

148,836

DESIGN FOR A KNIFE HOLDER

Bertram W. Coltman, Kenilworth, Ill., assignor to
Republic Molding Corporation, Chicago, Ill., a
corporation of Illinois

Application September 7, 1946, Serial No. 133,153

Term of patent 14 years

(Cl. D44—29)

To all whom it may concern:

Be it known that I, Bertram Wm. Coltman, a citizen of the United States, residing at Kenilworth, in the county of Cook and State of Illinois, have invented a new, original, and ornamental Design for Knife Holder, of which the following is a specification, reference being had to the accompanying drawing, forming a part thereof in which:

Fig. 1 is a perspective view of the knife holder showing my new design;

Fig. 2 is a side elevational view of the design shown in Fig. 1; and

Fig. 3 is a top elevational view of the design shown in Fig. 1.

The dominant features of my new design reside in separate knife compartments mounted upon a background panel, which background panel is provided with stepped portions along the

upper and lower edges of the panel, all as shown in the drawing.

I claim:

The ornamental design for a knife holder, substantially as shown and described.

BERTRAM WM. COLTMAN.
